UNITED STATES PATENT OFFICE.

ALBERT BALL, OF CLAREMONT, NEW HAMPSHIRE.

EMERY-WHEEL.

SPECIFICATION forming part of Letters Patent No. 277,659, dated May 15, 1883.

Application filed March 21, 1882. (No model.)

To all whom it may concern:

Be it known that I, ALBERT BALL, of Claremont, in the county of Sullivan and State of New Hampshire, have invented a new and useful Improvement in Emery-Wheels; and I do hereby declare that the following is a full and exact description of the same, reference being had to the accompanying drawings, and to the letters of reference marked thereon.

10 The object of the invention, which is to be hereinafter described and illustrated, is to so construct emery or other grinding and polishing wheels that the greatest strength will be obtained in conjunction with the lightest weight.

15 To the accomplishment of the above the invention consists, first, in providing said shell with suitable "stiffeners," which serve the double purpose of strengthening said wheel and affording means for holding the filling

20 mechanism thereon, and, second, in the novel method and means employed for supplying the grinding material to the shell. All these features are clearly shown in the accompanying drawings, which form part of this specification, and in which—

25 Figure 1 is a central vertical section of a wheel embodying my invention; Fig. 2, a sectional view taken on the line $x-x$, Fig. 1, and showing the manner of supplying the grinding material to the wheel.

30 Like letters refer to corresponding parts in the several views.

In the drawings, A represents a hollow wheel provided at its center with a suitable arbor-bearing, B, and with radial arms or spokes C. Upon the outer edges of the shell A are formed suitable flanges, D D, which extend a suitable distance above the rim of said shell, and have their inner faces sloping sufficiently to overlap the grinding material E', which is placed upon the outer circumference of shell A and between the flanges D D. These flanges D D may be cast with the shell, or may be secured thereto in any suitable manner; or one may be cast 40 with the shell and the other removably secured thereto. The face or outer circumference of shell A is concaved or recessed, the deepest point being at its center and midway between the flanges D D. When the grinding material has been applied to the shell, its outer surface being perfectly even throughout, it follows that its greatest thickness will be at

the point where the concavity formed between the flanges D D is the deepest—i. e., midway between said flanges, or at the center of the 55 face of shell A. I have found by frequent experiment that this construction is very desirable, and that it adds strength to the wheel and renders the displacement or breakage of the grinding material less liable; but I lay no 60 claim in this application to the construction thus far described, as it will form the subject-matter of another application to be filed.

Around the edges of the inner circumference of shell A are formed the stiffeners F, which 65 serve to strengthen said shell without adding much to the weight of the same, and are further used to receive and hold hook-shaped bolts G, used in connection with the devices for filling the wheel with grinding material, as 70 will now be described.

To cover the surface of the wheel with grinding material I first secure over the concavity formed between flanges D D a lag, H, which is held securely in place by hook-shaped bolts 75 G, before mentioned, the hooked ends of which are passed around the stiffeners F. Upon the opposite or outer ends of bolts G nuts I are secured, by means of which said bolts and the lag H are held in position. Upon the 80 upper face of flanges D D, and between said flanges and lag H, suitable strips, K, are placed, in order that the grinding material may extend slightly above the flanges D D. After the lag H has been secured on the shell in the 85 manner described a board, J, is placed upon the shell. This board J is placed vertically, and extends from the top of lag H down to the face of the shell, having its lower end made to conform to the shape of said shell and fitting as closely as possible over the projections E, formed between the flanges D D, when the construction shown in Fig. 3 is employed. This board J having been placed upon the shell, as described, another lag H is secured 90 to said shell in the same manner as before mentioned, and into the space formed between the face of the shell and this second lag the grinding material is forced, the board J forming an abutment against which the said material is 95 forced. These steps having been taken and the grinding material tamped as hard as possible, another lag is secured upon the shell in front of the second lag mentioned and the space

formed under said lag filled, as above described. This is continued until the entire grinding-surface is formed, the board or abutment J being removed previous to the filling 5 of the last space. In Fig. 2 of the drawings I have clearly illustrated the means employed in this filling process.

Having thus described my invention, what I claim as new therein, and that for which I desire to secure Letters Patent, is—

1. The within-described method of applying grinding material to a wheel, which consists of securing to said wheel lags and an abut-

ment and then forcing the material into the space formed between the surface of the wheel 15 and the lags, substantially as described.

2. In the grinding and polishing wheel described, the shell A, provided with stiffeners F, and in combination with bolts G and lags H, as and for the purpose set forth. 20

This specification signed and witnessed this 1st day of March, 1882.

ALBERT BALL.
